UNITED STATES PATENT OFFICE.

ALMON F. HILL, OF PORTLAND, MAINE.

ACETYLENE-GAS GENERATOR.

SPECIFICATION forming part of Letters Patent No. 679,620, dated July 30, 1901.

Application filed September 4, 1900. Serial No. 28,914. (No model.)

To all whom it may concern:

Be it known that I, ALMON F. HILL, a citizen of the United States, residing at Portland, in the county of Cumberland and State of Maine, have invented certain new and useful Improvements in Acetylene-Gas Apparatus; and I do hereby declare the following to be a full, clear, and exact description of the invention, such as will enable others skilled in the art to which it appertains to make and use the same.

My invention relates to improvements in acetylene-gas apparatus.

The object of my invention is to provide an apparatus which shall be self-regulating so far as relates to the production of a constant supply of gas, which it does by causing the carbid to be automatically subjected to water only when the quantity of gas in the gasometer is reduced below a certain amount; and my invention relates particularly to the construction of the gasometer and generator, so that they coöperate to produce this result. It is designed to be a simple, cheap, and safe apparatus for the manufacture and storage of acetylene gas.

In the drawings herewith accompanying and making a part of this application, Figure 1 is a central sectional view of my improved apparatus with parts broken out. Fig. 2 is a top plan view of the same with portions removed; and Fig. 3 is a central sectional view, partly in elevation, showing my invention as applied to a series of generators.

35 Same letters of reference refer to like parts. In said drawings, A represents the generating-chamber, in the top of which is suspended a basket or holder B for the carbid. This basket is made with openings at the bottom or bottom and side by being made of slats or wire spaced apart, so that while it supports the carbid it offers no obstruction to the passage therethrough of water to the carbid. The portion of the generating-chamber which supports the basket is surrounded by a loosely-suspended bell C, extending down outside of the generating-chamber, and this may be held in place against upward movement by brackets or levers D, secured to the extension E of the generator-casing and the top of said bell. The chamber F between the wall of the generating-chamber and extension E

is filled with water until the bell C is separated from the generating-chamber by a complete water seal.

55

At some point outside of the generating-chamber is a gasometer, which consists of an outside casing or tank G and a hollow chamber H, opening upwardly therein. The tank outside of chamber H is nearly filled with water. Adapted to float in this tank or reservoir is a gas-bell I, having a dependent plunger J, which enters chamber H and is adapted to reciprocate therein as the bell rises or falls as the quantity of gas in the bell varies. Connecting chamber A below the carbid-holder in the generator and chamber H is a pipe L, giving free communication between said chambers. At some point in pipe L is a water-supply pipe M, through which water can be introduced. The upper end of pipe M should be above the level of the carbid-basket.

Chamber A of the generator is provided with means for removing the residuum of the carbid—as, for example, with an outlet-pipe N and closing-valve O.

From bell C the gas passes through pipe P and wash-tank Q, and thence through pipe R into the gasometer, terminating above the water in the water-tank. The vertical portion of pipe R extends downwardly below the horizontal part and into a condenser S, as seen at T in Fig. 1. The wash-tank may be filled through the open pipe U, which extends below the surface of the water in the tank.

Leading from bell I is a distributing-pipe V. Communicating with pipe V is a safety blow-off pipe V', extending down into the condenser S and thence again to the outside, water being admitted to the blow-off pipe through the open end of the lower extension W. The blow-off may terminate at any point, even outside the building.

Secured to the top of tank G is a bracket X, carrying a dependent guide Y, which projects down into the head of the chamber and helps to guide the bell as it moves up and down.

It is found in actual use that there is a practical limit to the size of generators and that a single generator for lighting a city is impractical. Consequently it is found advisable where a large quantity of gas is desired

to have a series of generators. In Fig. 3 I have shown my invention adapted to be applied to such a series. It will be evident that the number of the series may be as many as is desired. They should be arranged so that the carbid in each should be at different elevations, the lower being first acted upon.

Referring to Fig. 3, it will be seen that each generator has a pipe L, corresponding with the similar pipe in Fig. 1, all uniting and communicating with the chamber H in the gasometer-tank.

The operation of my improved apparatus is as follows: The carbid is placed in the basket and water introduced through pipe M until it rises in the generating-chamber and in chamber H below the basket to the level of the carbid in the basket. Gas is generated thereby, passing up into bell C and thence through the pipe to the wash Q, and thence through pipe R into the gasometer, raising the bell and the plunger in chamber H. The lifting of said plunger causes the level of the water in said chamber and in the generating-chamber to fall below the carbid, and consequently the generation of gas ceases. As soon, however, as the supply of gas is sufficiently consumed the bell in the gasometer descends, raising the water in the generating-chamber until it reaches the carbid again, so that whenever there is a predetermined amount of gas in the gasometer the generation of gas is stopped, and whenever the amount of gas in the gasometer falls below a certain amount the generation of gas is again started automatically. It will be evident that in practice the water will be constantly in contact with the carbid so long as the consumption of gas goes on. When there is a series of generators, water is introduced into the pipe M until it reaches the level of the carbid in the first of the series of generators and the operation is the same as herein described for the single generator. When, however, all of the carbid in the first generator is used and the supply of gas is sufficiently lessened, the plunger descends further and raises the level of the water until it reaches the carbid in the second generator, and so on throughout the entire series.

The advantages of my improved apparatus are that it is simple in construction and requires no regulation, excepting to keep the carbid-basket supplied.

It will be evident that the details of construction can be varied greatly from that shown in the drawings—as, for instance, the gas-holder in the generator might serve also as the gas-chamber, the pipe conveying gas to the gasometer terminating in the basket

or holder itself. It will also be evident that any convenient blow-off or wash can be substituted for those shown in the drawings without varying the principle of my invention. 65

Having thus described my invention and its use, I claim—

1. In an acetylene-gas apparatus, a generator having a water-chamber, means for suspending carbid in said chamber, a gas-chamber above said water-chamber, a gasometer consisting of a water-tank and an inner chamber therein, a water-pipe leading from the water-chamber of the generator to and communicating with the interior of said inner chamber, whereby the level of the water in the generating-chamber varies according to the change in the level of the water in said inner chamber, a bell mounted in said tank and provided with a plunger adapted to reciprocate in said inner chamber and a gas-pipe leading from said gas-chamber in the generator to the gas-chamber in the gasometer. 75

2. In an acetylene-gas apparatus, a generator having a water-chamber, means for suspending carbid in said water-chamber, a gas-chamber above said water-chamber and means for introducing water into said water-chamber, a gasometer having a water-tank with an inner chamber open at the top, a gas-bell 90 having a plunger adapted to reciprocate in said inner chamber, means for connecting the water-chamber of the generator with the bottom of said inner chamber in the gasometer, whereby the level of the water in the generating-chamber varies according to the change in the level of the water in said inner chamber, and means for conducting gas from the gas-chamber of the generator to the bell of the gasometer. 95

3. In an acetylene-gas apparatus, a series of generators, each having a water-chamber below the carbid-receptacle, means for suspending carbid in said generator, the carbid in each being at different elevations and a gas-chamber above said water-chamber in combination with a gasometer having a water-tank, an inner chamber open at the top, a gas-bell with a plunger adapted to reciprocate in said inner chamber, a common water communication between the water-chamber of the generator and the inner chamber of the gasometer and means for conducting gas from the gas-generator to the bell of the gasometer. 110

In testimony whereof I affix my signature, 115 in presence of two witnesses, this 31st day of August, 1900.

ALMON F. HILL.
